ASSIGNOR OF ONE-THIRD TO HENRY STAPLES, OF STAMFORD,
CONNECTICUT.

GAME APPARATUS.

No. 851,493.

Specification of Letters Patent.

Patented April 23, 1907.

Application filed November 2, 1906. Serial No. 341,734.

To all whom it may concern:

Be it known that I, LEGER JEROME CASTONGUAY, a subject of the King of Great Britain, and a resident of Thompsonville, in the county of Hartford and State of Connecticut, have invented a new and Improved Game Apparatus, of which the following is a full, clear, and exact description.

The object of the invention is to provide a new and improved game apparatus, more especially designed for playing parlor base ball, and arranged to require considerable skill on the part of the players to successfully play the game, and to afford amusement for the players as well as the onlookers.

The invention consists of novel features and parts and combinations of the same, which will be more fully described hereinafter and then pointed out in the claims.

A practical embodiment of the invention is represented in the accompanying drawings forming a part of this specification, in which similar characters of reference indicate corresponding parts in all the views.

Figure 1 is a perspective view of the improvement; Fig. 2 is an enlarged sectional side elevation of the batting device; Figs. 3 and 4 are perspective views of the adjoining ends of the sides of the frame; Fig. 5 is a perspective view of one of the base ball catchers, and Fig. 6 is a perspective view of the base ball and the runner balls used in the game.

The frame A of approximately diamond-shape, is adapted to be placed on a floor, table or other suitable support, and is formed of the sides A', A², A³, A⁴ and the plate A⁵ fitting between the adjacent ends of the sides A' and A⁴, as plainly indicated in Fig. 1, the said sides and plate being removably connected with each other by suitable fastening devices such as hooks B and pins B', and dowel pins B² engage recesses B³, as plainly indicated in Figs. 3 and 4. By the arrangement described the sides and plate can be readily taken apart and packed in a small bundle to take up little room when transporting or storing the apparatus. The corners of the frame are provided with recesses A⁶, A⁷, A⁸ and A⁹ connected with each other by grooves A¹⁰ formed lengthwise on the top of the several sides, so as to connect the several recesses A⁶, A⁷, A⁸ and A⁹ with each other. As shown in Fig. 1, the recess A⁶ is at the home base, while the recesses A⁷, A⁸

and A⁹ are at the first, second and third bases. Now in order to represent the run of a player from one base to another, runner balls C are used, contained at the beginning of the game in the home base recess A⁶ and propelled one at a time by the batter or player from the recess A⁶ along the groove A¹⁰ in the side A' to the recess A⁷ at the first base. When the player takes position at the first base he can then propel the ball from the recess A⁷ to the recess A⁸ along the groove A¹⁰ in the side A², and the player after taking position on the second base can propel the ball along the recess A¹⁰ in the side A³ to the third recess A⁹, and finally propel it from the latter along the groove A¹⁰ in the side A⁴ back to the home recess A⁶.

On the plate A' of the frame A is arranged the batting device D having a post D' in which is mounted to turn a shaft D², on the forward end of which is fulcrumed a miniature bat D³ adapted to strike a base ball E for propelling the same across the frame as hereinafter more fully described. The bat D³ is connected near its fulcrumed end by a link D⁴ with a hand lever D⁵ fulcrumed on the rear end of the shaft D² and adapted to be taken hold of by the operator for turning the shaft D² and for imparting a swinging motion to the bat D³, so that the batter having hold of the handle D⁵ can bring the bat D³ in the direction in which the base ball E is coming, at the same time imparting a swinging motion to the bat so as to bat the ball across the frame A. Now the ball E thus propelled by the bat D³ is adapted to be caught in one of a number of catching cups F, preferably of conical shape, and provided with a handle F' connected by a string or rope G with an eye H attached to a side of the frame A, it being understood that four such catching cups F are provided and connected with the different sides A', A², A³ and A⁴ of the frame A, short distances from the first, second and third bases. The handles F' of the different catching cups F are taken hold of by the different players stationed outside of the frame A and representing first base man, second base man, short stop, and third base man, and when the base ball E is propelled by the bat D³ then a player having a catching cup tries to catch the ball E in his cup F, the sweep of the latter being limited by the corresponding cord or rope G.

In playing the game, the pitcher standing outside of the frame A throws the ball towards the bat D³ manipulated by the batter, with a view to bat the ball E out across the frame, the ball being caught by one of the players manipulating a corresponding receiving cup F. In the meantime, the batter, after the ball is propelled, rolls one of the runner balls C from the recess A⁶ along the groove A¹⁰ in the side A' to the first base recess A⁷, and if the ball E reaches the cup F connected with the side A' and located adjacent to the first base and is deposited in the recess A⁷, then the batter is out and the runner ball C is taken from the groove A¹⁰. If, however, the ball E is not returned to the cup adjacent to the first base previous to the runner ball C reaching the recess A⁷, then this runner ball remains there and the player is stationed alongside of the same or the player, if the chance is favorable, can propel the ball to the next recess A⁸ on the second base, and so on, the same as the player of real base ball passes from one base to the other. If desired, a catcher having a handled cup F may be placed behind the pitcher to catch the ball E when not hit by the bat D³.

From the foregoing it will be seen that by the arrangement described real base ball is closely imitated, and the rules governing base ball are followed as much as possible, it being understood that the runner ball C imitates the running from one base to the other, and when a runner ball C is returned to the home recess A⁶ then it counts for the playing side the same as in ordinary base ball.

The game apparatus is very simple and durable in construction and affords considerable amusement to the players as well as the onlookers, and it requires considerable skill in successfully playing the game.

Having thus described my invention, I claim as new and desire to secure by Letters Patent:

45 1. A game apparatus comprising a diamond-shaped frame having bases at the corners, a batting device at the home base, and manually actuated catching devices having flexible connections with the frame to limit their sweep.

2. A game apparatus comprising a frame having bases, a batting device at the frame for sending a ball across the frame, manually actuated catching devices having a limited movement for catching the base ball, and manually projected runners adapted to travel along the frame from one base to another.

55 3. A game apparatus comprising a dia-

mond-shaped frame having bases at the corners, a batting device at the home base, manually actuated catching devices having flexible connections with the frame to limit their sweep, and runways on the sides of the frame from one base to another to allow a manually propelled runner ball to travel from one base to the other.

4. A game apparatus comprising a diamond-shaped frame having its corners provided with bases and its sides with runways for a runner ball to travel from one base to another, a batting device at the home base, and base ball catching devices attached to the frame to limit their sweep.

5. A game apparatus comprising a diamond-shaped frame provided at each corner with a recess and along each side with a groove from one recess to the other, a batting device at the home base of the frame, handled cups for catching the base ball, and flexible connections between the said handled cups and the said frame.

6. A game apparatus comprising a diamond-shaped frame provided at each corner with a recess and along each side with a groove from one recess to the other, a batting device at the home base of the frame, handled cups for catching the base ball, and strings connecting the handles of the said cups with the sides of the said frame.

7. A game apparatus comprising a diamond-shaped frame provided at each corner with a recess and along each side with a groove from one recess to the other, a batting device at the home base of the frame and provided with a base ball bat, a shaft mounted to turn and on which the said bat is fulcrumed, a handle fulcrumed on the said shaft for turning the latter, and a link connecting the said handle with the said bat for imparting a swinging motion thereto, handled cups for catching the base ball, and flexible connections between the said handled cups and the said frame.

8. A baseball game apparatus provided with a batting device comprising a bat, a shaft mounted to turn and on which the bat is fulcrumed, a handle fulcrumed on the said shaft, and a link connecting the said handle with the said bat.

In testimony whereof I have signed my name to this specification in the presence of two subscribing witnesses.

LEGER JEROME CASTONGUAY.
